[57] **ABSTRACT**

An auxiliary rudder that is attachable to any outboard motor so to serve as a steering device; the auxiliary rudder consisting of a flat steel plate to each opposite side of which an offset bracket is secured, a pair of shims between each bracket and the plate, each bracket extending beyond a side edge of the plate and supporting a tension coil spring therearound so to be securely fitted to the outboard motor.

1 Claim, 4 Drawing Figures

PATENTED AUG 13 1974

AUXILIARY RUDDER

This invention relates generally to rudders for small boats.

A principal object of the present invention is to provide an auxiliary rudder that is attachable to an outboard motor, and which will give a person running his outboard motor full control of his steering at all times.

Another object is to provide an auxiliary rudder which will give full control of the steering even when the motor is dead.

Another object is to provide an auxiliary rudder which will enable a boat while trolling to be kept in a straight line or to turn suddenly while giving the boat operator a full control of the boat.

Yet another object is to provide an auxiliary rudder which will act as a steering device instead of depending on the motor propellor for steering.

Other objects are to provide an auxiliary rudder which is simple in design, inexpensive to manufacture, rugged in construction, easy to use, and efficient in operation.

These and other objects will be readily evident upon a study of the following specification and the accompanying drawing, wherein:

FIG. 1 is a side view of the invention.

FIG. 2 is a top view thereof.

FIG. 3 is a side view of a slightly modified design thereof in which the mounting structure is at a lower part thereof.

FIG. 4 is a perspective view of some representative components of the invention.

Referring now to the drawing in detail, the reference numeral 10 represents an auxiliary rudder according to the present invention, wherein there is a flat sheet metal plate 11 that may be made of 16 gauge material and which may measure 8 inches by 8 inches square. Two sets of two holes 12 are drilled through the plate for receiving mounting bolts 13.

Adjacent each side of the plate 11 a pair of sheet metal shims 14 are placed, each shim having a pair of openings 15 for alignment with openings 12. The shims may be also of 16 gauge material and may measure 1½

by 2 inches in size.

Adjacent each outer shim, there is a bracket 16 having openings 17 for alignment with openings 15. Each bracket may be likewise of 16 gauge sheet metal and may measure 1½ inch wide and about 6½ inches long.

The shims and brackets are fitted on by the bolts 13, as shown in the drawing, after which a washer 18 and securing nut 19 are fitted on the bolt.

Each bracket has an offset end 20 extending beyond a side edge 21 of the plate. Each bracket has a struck out hook 22 formed on the offset portion, and opposite ends of a tension coil spring 23 are attached on the hooks, thus allowing the spring to securely hold around a supporting object.

As shown in FIG. 1, the mounting structure can be secured to the upper set of holes 12, or as shown in FIG. 3, it can be secured to the lower set of holes 12.

While various changes may be made in the detail construction, it is understood that such changes will be within the spirit and scope of the present invention as is defined by the appended claims.

I claim:

1. In an auxiliary rudder, the combination of a flat plate that is 8 inches by 8 inches square, and mounting structure securable to said plate so that it can be supported from an outboard motor, said mounting structure comprising a pair of shims on each side of said flat plate, a bracket adjacent the outer shim, and a tension coil spring supported at its ends by the brackets, each bracket measuring 1½ inch wide and about 6½ inches long, having an offset end extending beyond a side edge of said plate, each offset end having a formed hook for securing said spring ends, said mounting structure being affixed either to a lower part or a center rear edge area of said plate, said plate, said shims and brackets being secured together by a pair of bolts fitted through aligned openings through said plate, shims and brackets, said bolts each receiving a washer and securing nut.
